UNITED STATES PATENT OFFICE

CHARLIE T. JONES, OF POPLAR BLUFF, MISSOURI

AEROPLANE

Application filed October 23, 1929. Serial No. 401,765.

This invention relates to improvements in aeroplanes, the general object of the invention being to provide novel means for controlling the movements of the ship from a point adjacent the pilot's seat, such means including means for adjusting a horizontal rudder at the tail of the ship, with means for holding the rudder in adjusted position and means for causing the ship to turn in either direction, such means causing the ship to bank on the turn.

Another object of the invention is to provide means for automatically bringing the ship back to an even keel when the ship tilts sidewise.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevation with parts broken away, to show the interior parts.

Figure 2 is a section on line 2-2 of Figure 1.

Figure 3 is a section on line 3-3 of Figure 2.

Figure 4 is a section on line 4-4 of Figure 3.

Figure 5 is a section on line 5-5 of Figure 3.

Figure 6 is a section on line 6-6 of Figure 3.

Figure 7 is a view of the two operating shafts with the hollow shaft in section, this view also showing a part of the rudder moving means operated by the hollow shaft.

Figure 8 is a sectional view through the wing.

In these drawings, the letter A indicates the fuselage of the ship which carries the usual propeller 1, the motors 2 and the landing gear 3. The wing is indicated at B. A horizontal rudder 4 is pivoted at the tail of the fuselage and has a vertical part 5. Upper

and lower cables 6 connect the rudder with a lever 7 pivoted at its center to an interior part of the fuselage, with its ends extending through slots in the fuselage. A sliding bar 8 is arranged in the bottom of the fuselage and has the uprights 9 connected with its forward part and the rear end of the bar is connected with the lower end of the lever so that when the bar is moved, the lever will be rocked to tilt the rudder.

A shaft 10 is supported for rotary and sliding movement in the fuselage and this shaft passes through holes in the upper ends of the uprights 9 and has a hand wheel 11 secured to its rear end which is adjacent to the pilot's seat 12. This shaft has the collars 13 fastened thereto between which the upper end of one of the uprights is arranged, so that by moving this shaft longitudinally by means of its hand wheel, the bar is moved forwardly or rearwardly to cause the lever 7 to tilt the rudder 4 to cause the ship to ascend or descend.

A hollow shaft 14 is rotatably mounted on the shaft 10 and passes through the instrument board 15, the shaft 10 also passing through this board. Handles 16 are attached to the rear end of the shaft 14 and these handles can also be reached by the pilot in the seat 12. This hollow shaft has the collar 17 attached thereto and this collar contacts the rear side of the rear upright and the front end of the hollow shaft abuts the rear collar 13, so that the hollow shaft will move longitudinally with the shaft 10, but can be rotated on said shaft 10. Said hollow shaft is externally threaded, as shown at 18, and the threaded part passes through a nut 19 which carries the oppositely arranged arms 20. A pair of springs 21 is connected to the board 15 and to the outer ends of the arms 20 and a pair of springs 22 is fastened to the arms and to a cross piece 23 in the fuselage through which the shaft 10 passes. As before stated, the hollow shaft is caused to move with the shaft 10 when said shaft is moved longitudinally and as the nut 19 and its arms 20 move with the hollow shaft 14, either one set of springs or the other set will be tensioned according to the direction of movement of the

shafts. For instance, if the shafts are pushed forwardly, the rear springs will be tensioned and the front springs will be slackened so that when the shafts are released by the force pushing them forwardly, the rear springs will move the shafts rearwardly until the tension of the front springs balances the tension of the rear springs and then the parts will come to rest. The parts are normally in a position with the front and rear springs tensioned an equal amount to hold the shafts, the uprights and the bar 8 with the rudder in a straight line. By moving the shafts longitudinally, the rudder will be tilted in one direction or the other, as before explained, and this movement of the shafts will tension one pair of springs so that these springs will return the parts to neutral position when the handle 11 is released. If it is desired to hold the rudder tilted for some time, the shafts are moved longitudinally to properly tilt the rudder, which, of course, tensions one set of springs, and slackens the other set and then, while holding the shafts in this position, the hollow shaft is turned by its handles 16 so as to adjust the nut 19 and its arms to a position which will equalize the tension of the two sets of springs so that these springs will then hold the shafts and, therefore, the rudder in their adjusted position. This arrangement provides means for keeping the ship on its course without attention from the pilot. The nut is held against turning movement with the hollow shaft by the rods 24 fastened to stationary parts in the fuselage and passing through the ends of the arms 20.

An aileron 25 is arranged at each side of the body, the forward ends of the ailerons being supported for rocking movement, as shown at 26. A bar 26' is attached to the inner side of each aileron and extends rearwardly and a sleeve 27 is slidably and rotatably arranged on said bar. Each sleeve is pivoted to a sleeve 28 slidably and rotatably arranged on a cross bar 29 which passes transversely through the fuselage and is pivoted at its center to a hanger 30 in the fuselage so that when the bar 29 is tilted in one direction, one aileron will be raised and the other lowered and vice versa. A pair of longitudinally extending bars 31 is each pivoted intermediate its ends to a part in the fuselage and the rear end of each of these bars is connected to the bar 29 by a pair of sleeves 32 arranged similarly to the sleeves 27 and 28. The forward ends of the bars 31 are connected by the sleeves 33 to the ends of a cross bar 34 pivoted at its center to a hanger 35. A slotted arm 36 is connected with the pivotal point of the bar 34 and the upper end of a stem 37 of a weight 38 is pivoted in the slot of the arm. These parts are so arranged that the weight is free to swing on its pivot in the arm when the ship tips longitudinally, but a slide slip of

the ship will cause the weight to act to turn the bar 34 on its pivot so that the bars 31 and the bar 29 will be moved and thus the ailerons will be adjusted to bring the ship back to an even keel.

A pair of drum shafts 39 is longitudinally arranged in the forward part of the fuselage and these shafts are rotated from the shaft 10, when the same is rotated, through means of the gears 40. Each shaft 39 carries a small drum 41 and a large drum 42. The weight is arranged between the small drums and a cable 43 connects each small drum with the weight. These parts are so arranged that while one cable is being wound on its drum, the other cable is unwinding from its drum so that by turning the shaft 10, the weight can be shifted in either direction and thus cause the ailerons to be adjusted to make the ship tilt to either side, as the pilot desires.

Side rudders 44 are each hinged at its forward end to a side of the fuselage forwardly of the ailerons, and these rudders are normally held against the sides of the fuselage by a spring 45. A forwardly extending arm 46 is connected to the inner face of each rudder and a cable 47 is connected with the front end of each arm and is wound around the large drum 42 which is farthest from the arm. The cables pass downwardly over the drums so that while one cable is being wound on its drum, the other cable will be unwinding from its drum so that the side rudders will work opposite to the ailerons and thus the ship will be caused to turn toward the side the rudder of which has been moved outwardly by the pilot and by turning the shaft 10, the pilot operates the side rudder and the ailerons simultaneously. Thus the pilot can control the movements of the ship from his seat by partly rotating the shaft 10 and moving the same longitudinally.

I prefer to make the wing B of hollow construction and gas-tight, so that gas can be introduced into the same through the inlet 48 so as to make the wing buoyant, and this gas can be discharged as desired through the outlet valve 49 by the pilot pulling upon the cable 50 which is connected to the valve and leads to a point near his seat.

Figure 5 shows a tank X in the upper part of the fuselage for containing water.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. An aeroplane comprising a body, a wing, a horizontal rudder, ailerons at the sides of the body and separated from the wing, side rudders hingedly connected with

the forward sides of the body, a longitudinally and rotatably arranged operating member, means for actuating the horizontal rudder by the longitudinal movement of said member and means for operating either side rudder and adjusting the ailerons to cause the craft to turn by the rotary movement of said member.

2. An aeroplane comprising a body, a wing, a horizontal rudder, ailerons at the sides of the body and separated from the wing, side rudders hingedly connected with the forward sides of the body, a longitudinally and rotatably arranged operating member, means for actuating the horizontal rudder by the longitudinal movement of said member, means for operating either side rudder and adjusting the ailerons to cause the craft to turn by the rotary movement of said member and means for automatically adjusting the ailerons to bring the craft to an even keel when the craft tilts sideways.

3. An aeroplane comprising a body, a wing, a horizontal rudder, ailerons at the sides of the body and separated from the wing, side rudders hingedly connected with the forward sides of the body, a longitudinally and rotatably arranged operating member, means for actuating the horizontal rudder by the longitudinal movement of said member, means for operating either side rudder and adjusting the ailerons to cause the craft to turn by the rotary movement of said member and means for holding the parts in a position with the horizontal rudder in adjusted position.

4. An aeroplane comprising a body, a wing, a horizontal rudder, ailerons at the sides of the body and separated from the wing, side rudders hingedly connected with the forward sides of the body, a longitudinally and rotatably arranged operating member, means for actuating the horizontal rudder by the longitudinal movement of said member, means for operating either side rudder and adjusting the ailerons to cause the craft to turn by the rotary movement of said member, means for automatically adjusting the ailerons to bring the craft to an even keel when the craft tilts sideways and means for holding the parts in a position with the horizontal rudder in adjusted position.

5. An aeroplane comprising a body, a wing, ailerons independent of the wing, side rudders hinged at their front ends to the forward sides of the body, means for normally holding the rudders against the sides of the body, a hand operated rotary member and means whereby the turning of said member in one direction will swing outwardly the rudder on one side of the body and lower the aileron on the opposite side of the body to cause the craft to make a banked turn in one direction and when the member is turned in an opposite direction, the other rudder will be swung

outwardly and the opposite aileron will be lowered to make the craft make a banked turn in the other direction.

6. An aeroplane comprising a body, a wing, ailerons independent of the wing, side rudders hinged at their front ends to the forward sides of the body, means for normally holding the rudders against the sides of the body, a hand operated rotary member and means whereby the turning of said member in one direction will swing outwardly the rudder on one side of the body and lower the aileron on the opposite side of the body to cause the craft to make a banked turn in one direction and when the member is turned in an opposite direction, the other rudder will be swung outwardly and the opposite aileron will be lowered to make the craft make a banked turn in the other direction and weighted means for automatically adjusting the ailerons to cause the craft to return to an even keel when the craft tilts sideways.

7. An aeroplane comprising a body, a wing, a horizontal rudder at the tail of the body, a shaft slidably arranged in the body and having a handle thereon for moving it longitudinally, a sliding member operated by the longitudinal movement of the shaft, a lever rocked by said sliding member, means for actuating the rudder from said lever, a hollow shaft rotatably arranged on the first shaft, a handle on the hollow shaft and means actuated by the turning movement of the hollow shaft for holding the sliding member in adjusted position.

8. An aeroplane comprising a body, a wing, a horizontal rudder at the tail of the body, a shaft slidably arranged in the body and having a handle thereon for moving it longitudinally, a sliding member operated by the longitudinal movement of the shaft, a lever rocked by said sliding member, means for actuating the rudder from said lever, a hollow shaft rotatably arranged on the first shaft, a handle on the hollow shaft, means actuated by the turning movement of the hollow shaft for holding the sliding member in adjusted position, such means comprising a cross piece having a threaded hole therein through which a threaded part of the hollow shaft passes whereby the cross piece will be moved by the rotary movement of the hollow shaft, springs connected to each side of the cross pieces, stationary parts to which the other ends of the springs are connected, so that by adjusting the position of the cross piece, the tension of the two sets of springs can be equalized whereby the springs will hold the parts in the position to which they have been moved and the rudder set in its adjusted position.

9. An aeroplane comprising a body, a wing, rudders hinged at their forward ends to the forward sides of the body, means for normally holding the rudders against the sides

- of the body, an arm connected to the inner face of each rudder and extending forwardly, a pair of drums, a cable connected to the front end of each arm and to a drum, a hand rotated member, means for rotating the drums from said member whereby when the member is rotated in one direction, one rudder will be swung outwardly and when the member is rotated in an opposite direction, the other rudder will be swung outwardly, an aileron at each side of the body and means operated by the rotary movement of the member for lowering one aileron when the rudder at the opposite side of the body is swung outwardly and for lowering the second aileron when the other rudder is swung outwardly.
10. An aeroplane comprising a body, a wing, rudders hinged at their forward ends to the forward sides of the body, means for normally holding the rudders against the sides of the body, an arm connected to the inner face of each rudder and extending forwardly, a pair of drums, a cable connected to the front end of each arm and to a drum, a hand rotated member, means for rotating the drums from said member whereby when the member is rotated in one direction, one rudder will be swung outwardly and when the member is rotated in an opposite direction, the other rudder will be swung outwardly, an aileron at each side of the body, means operated by the rotary movement of the member for lowering one aileron when the rudder at the opposite side of the body is swung outwardly and for lowering the second aileron when the other rudder is swung outwardly, such means comprising a drum connected with each of the other drums, levers for moving the ailerons, cables connecting the second drums with the levers, a weight connected with the levers for automatically operating the ailerons to bring the craft to an even keel when the same tilts sideways, a horizontal rudder at the tail of the body, means whereby the rotary member can be moved longitudinally and means operated by such movement for actuating the horizontal rudder.
11. An aeroplane comprising a body, a wing, rudders hinged at their forward ends to the forward sides of the body, means for normally holding the rudders against the sides of the body, an arm connected to the inner face of each rudder and extending forwardly, a pair of drums, a cable connected to the front end of each arm and to a drum, a hand rotated member, means for rotating the drums from said member whereby when the member is rotated in one direction, one rudder will be swung outwardly and when the member is rotated in an opposite direction, the other rudder will be swung outwardly, an aileron at each side of the body, means operated by the rotary movement of the member for lowering one aileron when the rudder at the opposite side of the body is swung outwardly and for lowering the second aileron when the other rudder is swung outwardly, such means comprising a drum connected with each of the other drums, levers for moving the ailerons, cables connecting the second drums with the levers and a weight connected with the levers for automatically operating the ailerons to bring the craft to an even keel when the same tilts sideways.

12. An aeroplane comprising a body, a wing, rudders hinged at their forward ends to the forward sides of the body, means for normally holding the rudders against the sides of the body, an arm connected to the inner face of each rudder and extending forwardly, a pair of drums, a cable connected to the front end of each arm and to a drum, a hand rotated member, means for rotating the drums from said member whereby when the member is rotated in one direction, one rudder will be swung outwardly and when the member is rotated in an opposite direction, the other rudder will be swung outwardly, an aileron at each side of the body, means operated by the rotary movement of the member for lowering one aileron when the rudder at the opposite side of the body is swung outwardly and for lowering the second aileron when the other rudder is swung outwardly, such means comprising a drum connected with each of the other drums, levers for moving the ailerons, cables connecting the second drums with the levers, a weight connected with the levers for automatically operating the ailerons to bring the craft to an even keel when the same tilts sideways, a horizontal rudder at the tail of the body, means whereby the rotary member can be moved longitudinally and means operated by such movement for actuating the horizontal rudder.

In testimony whereof I affix my signature.
CHARLIE T. JONES.
